UNITED STATES PATENT OFFICE

2,631,593

HAIR CURLING PAPER

Arthur H. Madore, Los Angeles, Calif.

Application January 2, 1951, Serial No. 203,921

1 Claim. (Cl. 132—36.2)

1

My invention relates to hair curling papers and among the objects of my invention are, to provide a simple, inexpensive and efficient paper which is especially designed to be used on the ends of the hair so that when wound thereon by a special hair pin or comb, will effectually curl the ends of the locks of hair to which it is applied.

Further objects of my invention are to provide a hair curling paper with small projections which are effective in combing out the end of a lock of hair to which the curler is applied; further, to provide the curler with apertures which when the device is applied to the hair, enables air to circulate freely through the hair being curled, and further, to so form the hair combing projections so that those on one side of the curler will act as small cups to hold oil, solution, or wave set that the user may apply to the hair.

With the foregoing and other objects in view, my invention consists in certain novel features of construction and arrangement of parts hereinafter more fully described and claimed, and illustrated in the accompanying drawing, in which:

Fig. 1 is a plan view of a hair curling paper constructed in accordance with my invention,

Fig. 2 is a fragmentary sectional view taken on the line 2—2 of Fig. 1,

Fig. 3 is a fragmentary sectional view taken on the line 3—3 of Fig. 1,

Fig. 4 is a sectional view of a modified form of the hair curling paper,

Fig. 5 is a plan view showing the manner of applying the paper to a lock of hair,

Fig. 6 is a perspective view of a curl formed with my improved paper,

Fig. 7 is a fragmentary view of a modified form of hair curler.

Referring by numerals to the accompanying drawing, 10 designates a square or rectangular piece of paper, foldable on a medial line a—b, to form two layers of equal size and formed in said paper are apertures 11 which function as air circulation openings during the drying of the hair curled by the device.

Also pressed in the paper forming the curler are teeth or indentations 12, the number thereof being much greater than the number of air circulation apertures, said indentations forming minute teeth which, as the paper is applied to the hair, combs and straightens the ends thereof. The pressure of the tool used in forming the teeth in the paper is such that there is no opening through the teeth, merely a very slight indentation. (See Figs. 2 and 3.)

2

These teeth may project from the same side of the sheet of paper as shown in Figs. 1, 2 and 3 or those formed on one side of said sheet may be pressed from the inside, outwardly and thus when the sheet is doubled upon the hair ends, the teeth that are pressed outwardly from the inside, may serve as minute cups to retain small quantities of oil, solution or wave set that may be used to lengthen the life of the curl. (See 10 Fig. 4.)

In applying my improved curler to the ends of a lock of hair, the latter is combed out half of the curling paper is placed beneath the lock of hair, a short distance from the ends thereof.

15 The upper half of the paper, shown by dotted lines Fig. 5, is now folded over onto the hair lying on the under half of the paper and the curler is drawn down onto the uneven ends of the hair as shown in Fig. 5.

20 Inasmuch as the hair is confined between the halves of the curler, the prongs 12 act as comb teeth in this operation, to hold said hair in proper position, and thus the uneven ends of the engaged lock of hair are retained in proper position until a hair pin x is slipped onto the lower end of the curler as shown in Fig. 5.

25 After the pin has been locked, the curler and contained lock of hair are rotated and at the termination of such rolling action, the pin is unlocked and removed and reinserted in the rolled paper and hair, with one leg of said pin on the outside of the paper and the other leg at the center of said roll, and the pin is now locked to maintain the paper and curl in rolled condition 35 while drying.

30 A variation of this rolling of the paper and hair is to withdraw the pin from the paper and hair while same are in flat condition and then produce the roll with both legs of the pin on the same side of the paper, thus, in effect, providing a mandrel, and at the termination of the rolling action, withdrawing the pin and applying same to the roll with one leg at the center thereof and the other on the exterior of the curl paper.

45 In the curling of the hair within the paper, the handle parts 12 and 13 of the comb shown in my application filed on Hair Curler, July 7, 1947, Serial Number 759,347, now abandoned, may be used, and also, the pin shown in said application is especially applicable in forming the curl.

50 In Fig. 7, I have shown the curl paper 10 provided on the rear face adjacent its lower end with a strip of light weight cardboard or the like 13, preferably half round in cross section and held in position by an adhesive, thus forming

an axis upon which the paper and hair are wound to produce the curl. After the curl has been formed, it is held in such condition by a pin, one prong of which extends through the member 13 and the other prong, on the exterior of the curl.

Thus, it will be seen that I have provided a hair curler that is simple in structure, inexpensive of manufacture, and very effective in performing the functions for which it is intended.

It will be understood that minor changes may be made in the size, form and construction of my improved hair curler without departing from the spirit of my invention, the scope of which is set forth in the appended claim.

I claim as my invention:

As a new article of manufacture, a hair curling paper, comprising a section of thin flexible material having a series of hair combing points pressed therein, which points are arranged so that when said thin material is folded double,

the points pressed from one section thereof, coincide with the points formed in the other section and there being air circulation openings formed throughout said section of thin material.
